E. C. SASNETT

AUTOMATIC TRAIN CONTROL SYSTEM

Filed August 7, 1925

UNITED STATES PATENT OFFICE.

EDWARD C. SASNETT, OF WASHINGTON, DISTRICT OF COLUMBIA.

AUTOMATIC TRAIN-CONTROL SYSTEM.

Application filed August 7, 1925. Serial No. 48,748.

The present invention relates to automatic train control systems of the continuous indication type.

One of the objects of the invention is to provide a continuous indication system in which the various indications are made dependent upon the reception of electrical impulses of a predetermined character. Another object is to provide a system of this type in which the signalling energy is transmitted to the vehicles through a third rail or power conductor. Other objects and advantages of the system will become apparent hereinafter.

As illustrated, the system is applied to a stretch of railroad on which vehicles are electrically propelled by continuous current, but it will be understood that the system is equally applicable to roads using alternating current.

Fig. 1 of the accompanying drawings is a diagrammatic view showing a system embodying the invention.

As customary in the signalling of roads using continuous propulsion current, the track is divided by insulated joints into blocks, with adjoining blocks connected by inductive bonds, which provide a free passage for power current flowing through the rails in parallel but prevent the passage of signalling current flowing through the rails in series. P designates the power rail divided by insulated joints into sections coincident with the block sections and provided with inductive bonds bridging the joints, whereby the rail is rendered conductive with respect to the continuous propulsion current, but is divided into insulated sections with respect to the alternating signalling current.

Each block is provided with a relay 10 connected across the rails at the entrance ends of the blocks and with a source of alternating signalling current connected at the exit ends, such sources, in the present instance, being portions of the secondaries of transformers T, the primaries of these transformers being connected across a pair of alternating current power mains.

Each block station is equipped with a single phase motor 200 geared to a cam disk 201. At station A the cam disk 201 has a raised portion extending through an arc of substantially 90°; at station B the raised portion extends through an arc of 180°; at station C the raised portion extends

through an arc of 90°. That is, the raised portions extend through arcs of 90° and 180° respectively at alternate stations. If it be assumed that the cam disks 201 make one revolution every four seconds, controller 202 at station A will connect the secondary of transformer T across the third rail and track of the block to the left of A, through the front contacts of relay 10 connected to block A, for a period of one second and disconnect it for three seconds every four seconds. At station B the controller 202 will connect the secondary of the transformer across the track and third rail for a period of two seconds and disconnect it for a period of two seconds every four seconds, etc.

On the vehicle there is a constant speed motor driving shafts 203 and 204 at uniform velocities. In alignment with shaft 203 is a shaft 205 and between the two shafts is an electro-magnetic clutch 206, which when energized connects the shafts for rotation together. Fixed on shaft 205 is an arm 207 carrying at its free end a brush 208 adapted to bridge stationary contacts 209 and 210. When the clutch is deenergized the arm is held by a spring 211 or equivalent means against a stop 212.

A shaft 216 is mounted in alignment with shaft 204 and adapted to be clutched thereto by an electromagnetic clutch 217. An arm 218 is fixed on shaft 216 and is held by a spring 220 against a stop 219 when the clutch is deenergized. The arm carries a brush 221 adapted to bridge stationary contacts 222 and 223. The circuits of stick relays 224 and 225 are controlled by the contacts 209, 210 and 222, 223, as will be presently pointed out. Under the joint control of the stick relays is a relay 226, which in turn controls any suitable train governing mechanism 227 and a clear signal lamp 228. The vehicle equipment also includes a solenoid 229 having its plunger connected to a dash pot 230, which operates to retard the downward movement of the plunger but permits a quick pick up thereof. The solenoid is adapted to be intermittently energized, as will appear, and so long as it is energized at predetermined intervals apart two pairs of contacts 231 and 232 are bridged. A relay 233 is adapted to flash the lamp 228 under certain conditions, as will hereafter be described.

With the vehicle in the block to the left of

A, and the latter clear, it will be understood from the foregoing that the relay 40 will be energized for one second and deenergized for three seconds, every four seconds. The 5 raised portion of cam 201 has just closed the controller 202 and the relay 40 is accordingly shown energized. The circuit of clutch 206 is closed from battery B through the front contact spring of relay 40 and the 10 arm 207 is just beginning its upward rotation. At the end of the one second period brush 208 has bridged contacts 209. When relay 40 drops, the following circuit is closed slightly in advance of the opening 15 of the circuit of clutch 206: battery B, conductor 234, back contact spring 235, conductor 236, contacts 209, conductor 237, conductor 238, stick relay 225, solenoid 229 and back to battery through conductors 239 and 240. The circuit of clutch 217 is also closed 20 at back contact spring 235 through conductors 241, 242 and 243. An impulse is thus sent through stick relay 225 and solenoid 229 and shaft 216 is clutched to motor 25 shaft 204. At the end of the three second interval in which relay 40 is deenergized brush 221 has bridged contacts 223, and when relay 40 picks up the following circuit will be closed slightly in advance of 30 the deenergization of clutch 217: battery B, conductor 234, from contact spring 244, conductor 245, contacts 223, conductors 246 and 238, relay 225, solenoid 229 and conductors 239 and 240 back to battery. Thus, as before, an impulse is sent through relay 225 35 and solenoid 229. It will be understood therefore that as long as the vehicle is in the block to the left of A, under clear conditions, impulses will be sent through relay 40 225 and solenoid 229, two every four seconds, there being a maximum interval of three seconds between impulses.

When the vehicle passes into block A, with 45 block B clear, it will receive signalling energy during the time controller 202 at station B is closed, and from what has been said before it will be understood that this energy will be in the form of impulses of two seconds duration separated by an interval of 50 two seconds. During the two second period in which relay 40 is energized arm 207 will move into a position where brush 208 bridges contacts 210; and when the relay is deenergized the following circuit will be momentarily closed: battery B, conductor 234, back contact spring 235, conductor 236, contacts 210, conductors 247 and 248, relay 224, solenoid 229 and conductors 239 and 240 back to battery. At the end of the two second 55 interval in which relay 40 is deenergized, brush 221 on arm 218 has bridged contacts 222 and when the relay picks up, the following circuit will be momentarily closed: battery B, conductor 234, front contact 60 spring 244, conductor 245, contacts 222, con-

ductors 249 and 248, relay 224 and solenoid 229, and conductors 239 and 240 to battery. Thus as before a momentary impulse is sent through stick relay 224 and solenoid 229. Thus as long as the vehicle is in block A, 70 with block B clear, impulses will be sent through stick relay 224 and solenoid 229, one every two seconds.

When relay 225 is picked up it is held by the following stick circuit: battery B, conductors 240 and 250, contacts 232, conductor 251, front contact 252, conductor 253, the winding of relay 225, front contact 254, conductors 255 and 256, contacts 231, and back to battery through conductor 257. When 80 relay 224 is picked up it is held by the following stick circuit: battery B, conductors 240 and 250, contacts 232, conductors 251 and 258, front contact 259, the winding of relay 224, conductor 260, front contact 261, conductors 262 and 256, contacts 231, and back to battery through conductor 257.

When the vehicle passes from block to block it is possible for an interval of five 90 seconds to intervene between impulses through the stick relays and solenoid 229. The action of the dash pot 230 is made such that the stick circuits are not opened unless the interval separating impulses is in excess of five seconds.

When both stick relays are energized a train control circuit is closed as follows: battery B, conductors 240 and 239, conductor 263, relay 226, front contacts of relays 225 and 224 in series, and back to battery 100 through conductor 264. Relay 226 when energized closes the circuits of suitable train control mechanism 227 and a green lamp 228.

When the vehicle enters a block directly in rear of an occupied block, it will no longer receive impulses, and accordingly at the end of three to five seconds from such entry the stick circuits of relays 224 and 225 will be opened, and these relays will drop, opening the circuit of relay 226, which in turn will open the circuits of train control mechanism 227 and green lamp 228. It is to be understood that the period of four seconds is given as the time for a complete cycle of operations merely by way of example. This period 110 may be varied as desired.

When a vehicle has once entered a block to the rear of an occupied block, and relays 224 and 225 have dropped, the train control devices cannot be cleared until the block in advance has been cleared and the vehicle enters this block at a time when the block in advance thereof is clear. That is, it is necessary that both stick relays 224 and 225 be energized in order to clear the train control devices, and this cannot occur until relay 40 has been operated by current in two adjacent blocks. Magnet 223 is provided to indicate, after the vehicle has entered a block to the rear of an occupied block, when 115 120 125 130

the latter is cleared. It will be observed that this magnet is intermittently energized upon reception of impulses from any block, and will therefore flash the lamp 228 when under the conditions stated the block in advance is clear.

Various changes may be made in the systems described and other substantially different modifications may be employed without departing from the scope of the invention as defined in the claims.

I claim:

1. In an automatic train control system, a track and a conductor parallel thereto, divided by insulated joints into blocks, a closed track circuit for each block including a relay, means controlled by the track relays for connecting between the track and conductor currents of different characteristics in the case of different blocks, a vehicle on the track having a translating device connected across the conductor and track, selective mechanism controlled by the translating device, train control devices, and means governed by the selective mechanism for clearing said train control devices when said translating device has been successively operated by currents of a plurality of said characteristics.

2. In an automatic train control system, a track and a conductor parallel thereto, divided by insulated joints into blocks, a closed track circuit for each block including a relay, means controlled by the track relays for connecting between the track and conductor of each block signalling currents having different characteristics in the case of adjacent blocks and the same characteristics in the case of alternate blocks, a vehicle on the track having a translating device connected across the conductor and track, selective mechanism controlled by the translating device, train control devices, and means governed by the selective mechanism for clearing said train control devices when the translating device has been successively operated by currents of different characteristics.

3. In an automatic train control system, a track and a conductor parallel thereto, divided by insulated joints into blocks, a closed track circuit for each block including a relay, means controlled by the track relays for connecting between the track and conductor of each block signalling currents having different characteristics in the case of adjacent blocks and the same characteristics in the case of alternate blocks, a vehicle on the track having a translating device connected across the conductor and track, two stick relays, selective mechanism controlled by the translating device adapted to close the pick-up circuit through one or the other relay upon reception of current of one or the other characteristic, slow acting means

for closing the stick circuits of the relays upon reception of current of either characteristic, and train control devices held at clear when both of said stick relays are energized.

4. In an automatic train control system, a track and a conductor parallel thereto, divided by insulated joints into blocks, a closed track circuit for each block including a relay, means controlled by the track relays for connecting between the track and conductor of each block signalling currents having different characteristics in the case of adjacent blocks and the same characteristics in the case of alternate blocks, a vehicle on the track having a translating device connected across the conductor and track, two stick relays, selective mechanism controlled by the translating device adapted to close the pick-up circuit through one or the other relay upon reception of current of one or the other characteristic, slow acting means for closing the stick circuits of the relays upon reception of current of either characteristic, train control devices held at clear when both of said stick relays are energized, and means for giving an indication when only one of said stick relays is energized.

5. In an automatic train control system, a track and a conductor parallel thereto divided by insulated joints into blocks, a closed track circuit including a relay for each block, a source of current connected through front contacts of the respective relays across the conductor and track of blocks immediately in rear of the respective relays, a circuit controller in each of said connections, constant speed motors and means operated thereby for closing and opening said controllers during regularly recurring periods, the periods during which the controllers pertaining to alternate blocks are closed and open being respectively equal and substantially unequal to the periods in which the controllers pertaining to the blocks adjacent thereto are closed and open, a vehicle on the track having a relay connected between the conductors and rails, a constant speed motor on the vehicle, switch mechanism operated by said vehicle motor and controlled by the vehicle relay, train control devices governed by said switch mechanism, and means controlled by the switch mechanism for preventing the clearance of the train control devices subsequently to the entry of the vehicle into a block immediately in rear of an occupied block until the latter has been cleared and the vehicle passes therein at a time when the block in advance is clear.

6. In an automatic train control system, a track and a conductor parallel thereto divided by insulated joints into blocks, a normally closed track circuit including a relay for each block, a source of current connected

- through front contacts of the respective track relays across the conductor and track of the blocks immediately in rear of the relays, a switch in each of said connections, constant speed motors and means operated thereby for closing and opening said switches during regularly recurring intervals, the periods in which the switches pertaining to alternate blocks are closed and open being respectively equal and substantially unequal to the periods in which the switches pertaining to the blocks adjacent thereto are closed and open, a vehicle on the track having a relay connected between the conductor and rails, a constant speed motor and two stick relays on the vehicle, switch mechanism operated by the vehicle motor and controlled by the vehicle relay, adapted to close a pick-up circuit through one or the other of said stick relays according as the durations of the periods in which the vehicle relay is energized and deenergized are determined by the operation of the switches pertaining to one block or the adjacent block, slow acting means operated when the pick up circuit of either stick relay is closed adapted to hold the relay energized for a predetermined time, and control devices held at clear so long as both relays are energized.
7. In an automatic train control system for electric roads, a track and a power conductor divided into blocks, means for connecting between the track and power conductor of each block a source of signalling current, when the block in advance is clear, means for affecting the current differently in the case of adjacent blocks, a vehicle having a translating device connected between the power conductor and rails, train control devices, and selective means controlled by said translating device for holding said train control devices at clear upon reception of current from any block and preventing said mechanism from being cleared when once at danger indication until said translating device has been affected by current from two adjacent blocks.
8. In an automatic train control system for electric roads, a track and a power conductor divided into blocks, a vehicle on the track having a translating device connected between the power conductor and track, means for transmitting impulses through the translating device at regularly recurring intervals under clear conditions, the duration of the impulses transmitted to the vehicle in any one block being different than that of the impulses transmitted to the vehicle when it passes into the adjacent block, two stick relays, selective means controlled by the translating device for closing a pick-up circuit through one or the other relay according as the impulses are received from one or the other of said blocks, slow acting means operating upon reception of each im-

pulse to hold closed stick circuits through the relays for a predetermined time, and train control devices held at clear so long as both of said stick relays are energized.

9. In an automatic train control system for electric roads, a track and a power conductor divided into blocks, a vehicle on the track having a translating device connected between the power conductor and track, means for transmitting impulses through the translating device at regularly recurring intervals, the duration of the impulses transmitted to the vehicle in any one block being different from that of the impulses transmitted to the vehicle when it passes into the adjacent block, train control devices, and selective mechanism controlled by said translating device for preventing the clearance of said train control devices until said translating device has been operated by currents from two adjacent blocks.

10. In an automatic train control system for electric roads, a track and a power conductor divided into blocks, a vehicle on the track having a translating device connected between the power conductor and track, means for transmitting impulses through the translating device at regularly recurring intervals under predetermined traffic conditions, the impulses transmitted being different in the case of adjacent blocks, train control devices, and selective mechanism controlled by said translating device for clearing said train control devices when the translating device has been operated by currents from two adjacent blocks.

11. In an automatic train control system for electric roads, a track and a power conductor divided into blocks, a vehicle on the track having a translating device connected between the power conductor and track, means for transmitting impulses through the translating device at recurring intervals under predetermined traffic conditions, the impulses being different in the case of adjacent blocks, two stick relays, selective means controlled by the translating device for closing a pick-up circuit through one or the other relay according as impulses are received from one block or the adjacent block, slow acting means controlled by the translating device for holding closed stick circuits for said relays for a predetermined time, and train control devices held at clear so long as both stick relays are energized.

12. In an automatic train control system for electric roads, a track and a power conductor divided into blocks, means for applying electrical energy to the power conductor of different characteristics in the case of different blocks, a vehicle traveling on the track having mechanism selectively responsive to said currents, train control devices on the vehicle, and means governed by said selective mechanism for clearing said train

control devices when said mechanism has been successively operated by currents of a plurality of said characteristics.

13. In an automatic train control system, a track and a conductor parallel thereto divided by insulated joints into blocks, a closed track circuit for each block including a relay, means controlled by the track relays for connecting between the track and conductor currents of different characteristics in the case of different blocks, a vehicle on the track having a translating device connected across the conductor and track, train control devices governed by said translating device, and mechanism selectively responsive to said currents of different characteristics for preventing the clearance of said train control devices until said mechanism has been selectively actuated by currents of a plurality of said characteristics.

14. In an automatic train control system, a track and conductor parallel thereto divided into sections, a vehicle on the track having translating devices energized from said conductor, means for energizing said conductor section with currents of different character in the case of adjacent sections, train control devices governed by said translating device, and mechanism selectively responsive to said currents for preventing clearance of said train control devices until said mechanism has been successively actuated by currents of said different characters.

15. In an automatic train control system, a track and a conductor parallel thereto, divided by insulated joints into blocks, a closed track circuit for each block including a relay, means controlled by the track relays for connecting between the track and conductor currents of different characteristics in the case of different blocks, a vehicle on the track having a translating device connected across the conductor and track, mechanism on the vehicle selectively responsive to said currents, train control devices, governed by said translating device and means governed by the selective mechanism for preventing the clearance of said train control devices until said mechanism has been successively operated by currents of a plurality of said characteristics.

16. In an automatic train control system, a track and a conductor parallel thereto, divided by insulated joints into blocks, a closed track circuit for each block including

a relay, means controlled by the track relays for connecting between the track and conductor of each block signalling currents having different characteristics in the case of adjacent blocks and the same characteristics in the case of alternate blocks, a vehicle on the track having a translating device connected across the conductor and track, mechanism on the vehicle selectively responsive to said currents, train control devices governed by said translating device and means governed by the selective mechanism for preventing the clearance of said train control devices until said mechanism has been successively operated by currents of different characteristics.

17. In an automatic train control system, a track and a conductor parallel thereto, divided by insulated joints into blocks, a closed track circuit for each block including a relay, means controlled by the track relays for connecting between the track and conductor of each block signalling currents having different characteristics in the case of adjacent blocks and the same characteristics in the case of alternate blocks, a vehicle on the track having a translating device connected across the conductor and track, two stick relays, mechanism selectively responsive to said currents adapted to close the pick-up circuit through one or the other relay upon reception of current of one or the other characteristic, slow acting means for closing the stick circuits of the relays upon reception of current of either characteristic, and train control devices governed by said translating device and held at clear when both of said stick relays are energized.

18. In combination, a way-side conductor divided into sections, means for applying electrical energy having two distinctly different characteristics respectively to two successive sections of said conductor, a vehicle having a stick relay, means controlled by said current for closing a pick-up circuit through said relay upon reception of current of one character and a holding circuit through said relay upon reception of current of the other character and train governing means controlled by said relay.

In testimony whereof I hereunto affix my signature.

EDWARD C. SASNETT.
